GASOLINE FILLER HOSE NOZZLE

Hugh H. Donovan, Montgomery, Ala.

Application May 23, 1938, Serial No. 209,559

3 Claims. (Cl. 226—66)

The invention relates to a liquid dispensing nozzle and more especially to a gasoline filler hose nozzle.

The primary object of the invention is the provision of a nozzle of this character, wherein its construction is such for attachability to a dispensing hose of a gasoline pump and such construction assures a warning to be had the instant that the tank for gasoline of a motor vehicle has 10 become filled and thereby eliminating an overflow from such tank and at the same time assuring against waste of the gasoline during the dispensing thereof.

Another object of the invention is the provision 15 of a nozzle of this character, wherein during the dispensing of gasoline for the filling of a gasoline tank, particularly those equipped on motor vehicles, a signal will be had showing that gasoline is being supplied to the said tank and the 20 instant that the tank is filled the signal stops thus signifying the fact that the tank has become filled and in this way avoiding the overfilling of such tank during the dispensing operation of the gasoline.

25 A further object of the invention is the provision of a nozzle of this character, wherein a novel closure member is associated therewith so as to enable the covering of the filling spout of a gasoline tank irrespective of the closeness of said 30 spout to the body of a motor vehicle having the tank a part of its equipment and such closure seals the mouth end of the spout so that in cooperation with the nozzle an overflow of the tank will be avoided and at the same time a notice 35 will be given the instant that the tank becomes filled with gasoline dispensed from the nozzle.

A still further object of the invention is the provision of a nozzle of this character, which is simple in its construction, thoroughly reliable and 40 efficient in operation, capable of fitting with the filling spout constituting parts of varying types of gasoline tanks and their arrangement in a motor vehicle in that some filling spouts are located in contracted areas making it difficult to 45 introduce the dispensing nozzle of a gasoline dispenser into the spout for the filling or supplying of the tank with gasoline from said dispenser, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary elevation of a gasoline tank constituting an equipment of a motor vehicle and partly in section showing the nozzle constructed in accordance with the invention, 5 being partly in section, inserted within the filling spout of said tank for the servicing thereof with gasoline.

Figure 2 is a fragmentary enlarged side elevation partly in section of the said nozzle. 10

Figure 3 is an end elevation of the nozzle looking toward the discharge end thereof showing in detail the closure associated with said nozzle for the filling spout of the tank.

Similar reference characters indicate corresponding parts throughout the several views in the drawing. 15

Referring to the drawing in detail, A designates generally a portion of a gasoline tank constituting a part of the equipment of a motor vehicle and includes a drum body 10, which at its top has in association therewith a filling spout 11 through which is introduced gasoline into the tank A in the usual well-known manner, while B denotes generally a gasoline dispensing nozzle 20 being connected with a delivery hose 12 in the usual way and this hose is a part of a gasoline dispenser of those employed at gasoline filling stations. 25

The nozzle B comprises a valved body 13, the 30 valve mechanism being indicated at 14 and is of the plunger operated cut-off type. This body 13 is provided with a discharge mouth piece or member 15, its passage 16 being in communication through the head 13 with the hose 12 for the 35 discharge of gasoline when the piece or member 15 is inserted within the filling spout 11 of the tank A, the valve mechanism being for controlling the delivery of the gasoline into the tank 40 for the filling thereof.

45 Swingably connected with the nozzle B at the under side of the body 13 is a trigger 17 which acts directly upon the plunger of the valve mechanism 14 so that the said valve mechanism can be operated manually in the usual manner for controlling the discharge of gasoline through the nozzle. This trigger is pivoted at 18 to a bearing 19 on the nozzle B and is in convenient reach to the user of the nozzle B when grasping the latter for the placement of the nozzle in the 50 filling spout 11 of the tank A so that the latter can be filled or supplied with gasoline as is commonly done at filling stations.

The part or member 15 of the nozzle B has integrally formed therewith or separably con- 55

nected thereto an air escape tube 20, which has the portion 21 carried beneath or in juxtaposition to a trigger guard 22 formed on the nozzle B. This portion 21 at its outer end has fitted therein an air-operated whistle or signal device 23. The end of the tube 20 approaching the free end of the part or member 15 of the nozzle B is removed therefrom and this end is designated at 24 so that when the nozzle is in use for the filling of a gasoline tank A, being engaged in the filling spout 11 thereof, there is no chance of gasoline escaping outwardly and discharging from the tube 20 during the filling operation or syphoning action being set up within the tube 20. The air under pressure resultant from the filling of the tank A with gasoline is let off from within said tank through the tube 20 and during escapement of this air under slight pressure the whistle 23 or other sounding device will operate, signaling an attendant using the nozzle B for the filling of the tank with gasoline of the fact that such tank is being filled. The instant the gasoline rises within the tank A to a level filling the same, the air through the tube 20 is cut off and the whistle or other like device 23 is silenced thereby giving notice to the attendant that the tank is filled so that the valve mechanism 14 may be operated for the shutting off of the flow of gasoline through the nozzle B and in this way gasoline saving is had.

The end 25 carrying the whistle or other device 23 constitutes a seat for a closure, gasket, stopper or the like 26 counterseated within a capping terminal 27 on the trigger 17 and when the valve mechanism 14 is in normal position shutting off gasoline flow through the nozzle B the end 25 of the portion 21 of the tube 20 is closed or sealed. When the valve mechanism 14 is operated by the trigger 17 for the flow of gasoline through the nozzle B, this cap terminal 27 is lifted from the end 25 and the gasket, stopper or the like 26 removed from the seat constituted by said end 25 and opening the tube 20 so that escape of air under slight pressure will actuate the whistle or signal device 23 when such air passes from within the tank A into the tube 20 concurrently with the filling of the tank A with gasoline. The whistle or other signaling device 23 constantly sounds or operates during the filling of the tank A with gasoline and the instant that the tank becomes filled with the gasoline the whistle or other signal device is silenced thereby notifying the attendant using the nozzle B that such tank has become filled.

About the part or member 15 of the nozzle B and also the tube 20 is a resilient capping disk or covering part 28 for the mouth end 29 of the spout 11. This part 28 has a straight side edge 30 while the opposite side edge 31 is rounded so that through the shaping of such part 28 the nozzle B is adaptable for insertion in the filling

openings or the filling spouts 11 of varying arranged gasoline tanks A equipped on motor vehicles where the said filling openings or spouts are in restricted or contracted locations thereon. This part 28, when the nozzle B is inserted in the filling opening or spout 11 of the tank A, will make contact with the mouth 29 and thus seal the same against escapement of gasoline or air from within the tank. The air is adapted to flow outwardly from the tank A through the tube 20 during the use of the nozzle B for the filling of the tank with gasoline. This flow of air operates the whistle or other signal device 23 during the filling operation. Instantly, when the tank becomes filled with gasoline dispensed through the nozzle B, the whistle or other signal device 23 is silenced and in this way notification is had that the tank is filled and the user of the nozzle B cuts off the flow of gasoline therethrough resulting in the saving of gasoline and avoiding the overfilling of the said tank A through the use of said nozzle.

What is claimed is:

1. The combination of a dispensing nozzle having a plunger with a flow control valve therein, an air escapement tube exteriorly of said nozzle for alignment with the control valve and spaced therefrom, a signaling device within said tube and operated by air flow therethrough, and a movable lever forming a trigger arranged within the space between the control valve and said tube for operating the said control valve and the opening and closing of said tube simultaneously.

2. The combination of a dispensing nozzle having a plunger with a flow control valve therein, an air escapement tube exteriorly of said nozzle for alignment with the control valve and spaced therefrom, a signaling device within said tube and operated by air flow therethrough, a movable lever forming a trigger arranged within the space between the control valve and the said tube for operating the said control valve and the opening and closing of said tube simultaneously, and a pivot connection between the nozzle and said lever.

3. The combination of a dispensing nozzle having a plunger with a flow control valve therein, an air escapement tube exteriorly of said nozzle for alignment with the control valve and spaced therefrom, a signaling device within said tube and operated by air flow therethrough, a movable lever forming a trigger arranged within the space between the control valve and the said tube for operating the said control valve and the opening and closing of said tube simultaneously, a pivot connection between the nozzle and said lever, and a head formed on said lever for accommodating an end adjacent thereto of the tube and having a sealing element counterseated therein for contact with the end of said tube.
